Application January 13, 1933, Serial No. 651,525

10 Claims. (Cl. 309—11)

This invention relates to pistons and more particularly to improvements in aluminum or other light metal alloy pistons for internal combustion engines.

5 This invention is an improvement particularly in the type of piston disclosed and claimed in the co-pending applications of George L. Moore, Serial No. 462,761, filed June 21, 1930, now Patent No. 1,926,611 and Frank Jardine, Serial No. 13 619,947, filed June 29, 1932, now Patent No. 1,939,778.

In the type of piston disclosed in said applications the excess thermal expansion of the light metal alloy of which the piston is composed over the thermal expansion of the cylinder in which the piston reciprocates is absorbed in part by a substantially vertical slot in the minimum thrust face of the piston terminating above the bottom of the piston skirt and intersecting a substantially horizontal slot separating the upper edge of the minimum thrust face only from the ring flange of the piston head, and in part by the contour of the piston. This novel arrangement provides an extremely simple piston which may be readily and easily cast in permanent molds and machined to final form, and one which compensates for the excess expansion of the light metal alloy while permitting a close fit without danger of slapping when the piston is cold, while at the same time retaining a full solid maximum thrust face with freedom for maximum heat flow from the head to the piston skirt, and avoiding excessive bending or flexing of the skirt under lateral thrust loads and consequent permanent deformation of the split portions of the skirt.

35 It has been found that although this type of piston has solved in a simple and economical manner most of the problems of piston design resulting from the unequal thermal expansion of a 40 light metal alloy piston and the cylinder in which the piston is employed, a tendency exists in some cases for the head portion of the piston to split off from the skirt and wrist pin boss portion by breaking open the metal in a continuation of 45 the horizontal slot between the upper edge of the minimum thrust face and the ring flange. This has apparently been due in part to the different action of the metal during expansion on the opposite sides of the piston, since on the maximum 50 thrust face side and in the portion above the wrist pin bosses the piston is a solid trunk type piston with a continuous integral connection between the ring flange and the skirt, whereas on the opposite side or minimum thrust face side of the 55 piston the upper edge of the skirt and the lower edge of the ring flange are separated. When a certain increment of circumferential expansion at the top of the skirt has been absorbed by the substantially vertical split, the upper edges of the 60 split portions of the minimum thrust face have

been swung like tongues along lines substantially intersecting the ends of the horizontal slot, and the vertical axis of the piston has been moved slightly from the vertical axis of the cylinder in the direction toward the split side of the skirt. 5 This tendency has apparently also been due in part to the inertia and power loads transmitted between the head and the wrist pin.

I have discovered that this tendency toward splitting off of the piston head may be overcome, 10 without increasing the weight of the piston or introducing complex internal contours which might tend to interfere with the simple manufacture of a piston in permanent molds, by providing the interior of the piston head and the 15 ring flange above the wrist pin bosses with a reinforcing bridge offset toward the split side of the piston from the vertical plane through the wrist pin axis. Preferably this reinforcing bridge is offset a sufficient distance so as to be disposed 20 entirely on the slotted side of the piston with respect to this vertical plane, and is of sufficient cross section to evenly distribute about this vertical plane the power and inertia loads transmitted between the head and the wrist pin. In 25 this manner the vertical legs of the reinforcing bridge are disposed closely adjacent the ends of the horizontal slot, and the intersection of the ring flange and the skirt on the maximum thrust side of the piston for a full 180 degrees is uniform, 30 thereby reducing the distorting forces arising from the movement of the metal when expansion is absorbed by closing of the substantially vertical slot.

In the accompanying drawing which illustrates 35 a preferred embodiment of the invention:

Figure 1 is a side elevation of the piston;

Figure 2 is a vertical sectional view taken substantially on the line 2—2 of Figure 1;

Figure 3 is a vertical sectional view taken on 40 the line 3—3 of Figure 2;

Figure 4 is a horizontal sectional view taken on the line 4—4 of Figure 1.

For purposes of clearance, the description is made on the assumption that the long axis of 45 the piston is vertical, as illustrated in the drawing, altho that axis may not be vertical when the piston is in its cylinder, as for example, in a V-type engine where the long axis of the piston may be inclined at an angle of 30 degrees to a vertical 50 cal line.

Referring to the drawing the piston illustrated is generally of the full trunk type piston including a head 11 having a depending cylindrical flange 12 grooved for the reception of piston packing rings and a skirt 13 integral with and depending from the lower edge of the ring flange 12. Piston pin bosses 14 are formed integrally with the piston skirt and with a reinforcing bridge work consisting of the vertical ribs 15 60

joined by a horizontal rib 16 extending across the underside of the piston head. The ribs 15 extend as shown from the wrist pin bosses upwardly to the piston head on one side of the vertical plane through the wrist pin axis. The vertical ribs 15 on one side merge into bosses 17. A thickened portion or pad 18 is formed in the inner surfaces of one thrust face.

The piston is preferably cast in permanent molds or the like in the same manner as a full trunk type piston, the offset ribs 15 and 16, the bosses 17 and the pad 18 being formed by the proper contours of the mold and core parts.

In machining the cast piston, radial holes 19 are drilled through the walls of the piston and through the bosses 17. These holes 19 are then connected by a substantially horizontal slot 20 which serves to separate the upper edge of one thrust face from the lower edge of the ring flange. This thrust face, indicated by the numeral 24, is called the minimum thrust face and is designed to be arranged in the engine to receive the lateral thrust of the compression stroke. The opposite thrust face 25, which remains continuously integral with the ring flange except the suitable oil holes and the like when desired, is called the maximum thrust face and is arranged in the engine to receive the lateral thrust of the power stroke. Holes 21 and 22 are drilled through the minimum thrust face 24 and through the reenforcement 18 and form the upper and lower termini, respectively, of a substantially vertical slot 23. The hole 21 intersects the horizontal slot 20 as shown in Figure 1 and the hole 22 is disposed within the lower end of the pad 18 as shown in Figure 3.

As illustrated in Figures 2 and 4 the holes 19 which form the ends of the horizontal slot 20 open through the bosses 17 immediately adjacent the vertical ribs 15 so that the metal at the ends of the horizontal slot is reenforced against splitting by the radial thickness of the ribs 15. The vertical ribs 15 and the horizontal ribs 16 form as a whole a reenforcing bridge work extending upwardly from each wrist pin boss and across on the under side of the head, all disposed on the slotted side of the piston with respect to the vertical plane through the wrist pin axis.

In operation the ribs 15 serve to carry the greater part of the compression and tension loads between the wrist pin bosses 14 and the head 11. The compression loads are caused by the explosive forces of the gas above the piston head which must be transmitted to the wrist pin journal 13 nailed in the bosses 14 and also by inertia, while the tension loads are produced entirely by inertia when the direction of motion of the piston is reversed. Without the reenforcing bridge a compression load applied to the entire top of the piston head would tend to rock the top downwardly on the slotted side, since the ring flange and skirt are integral about one side of the piston and separated by the slot 20 on the other side. Likewise the tension loads would tend, without the reenforcing bridge work, to spread the horizontal slot 20, since the piston head on that side is not connected to the skirt and on the opposite side is continuously integral with the top of the skirt. Obviously, exactly the same effect occurs when the usual reenforcing ribs for transmitting the loads from the head to the wrist pin bosses are employed, disposed directly in the vertical plane through the wrist pin axis. With the improved construction disclosed herein this tendency to rock the piston head from the

compression and tension loads is counteracted by the fact that the greater portions of these loads are transmitted through the ribs 15 spaced toward the slotted side of the piston from the vertical plane. Preferably this spacing is sufficient and the cross section of the ribs 15 is sufficient to uniformly distribute the loads to the two sides of the piston and to completely counteract the tendency of the head to rock with respect to the skirt.

Likewise the offsetting of the reenforcing bridge work minimizes the stresses set up at the ends of the horizontal slot 20 by the non-uniformity of the movement of the metal on the opposite sides of the piston which results from the fact that substantially all of the circumferential expansion of the top of the piston skirt is absorbed on one side by the closing of the vertical slot 23. As a consequence this improved structure practically eliminates the previously existing tendency in this type of piston for the head of the piston to separate from the skirt in use.

It will be understood that preferably the piston skirt is provided with an unsymmetrical contour as disclosed in the aforesaid co-pending applications of Jardine and Moore, although the present invention is not limited to this feature or to the exact slotting arrangement disclosed, since it is useful in any type of piston which is unsymmetrically slotted so as to create a tendency for the head to break off from the skirt under the power of inertia loads or the stresses set up by thermal expansion.

As shown by the drawing, the reinforcing ribbing, as a unit, is offset from the vertical plane thru the wrist pin bosses toward the slotted side of the piston. Since the ribbing is so offset, its center of mass is likewise offset and in the same direction.

What I claim is:

1. A piston composed of a light metal alloy and including a head having a depending ring flange and a skirt, diametrically opposed wrist pin bosses in the skirt, the upper edge of said skirt being continuously integral with the lower edge of the ring flange on one side of a vertical plane through the axis of the wrist pin bosses and being partially separated therefrom on the opposite side of such plane by a substantially horizontal slot, and reenforcing ribs integral with said wrist pin bosses and extending up to and integral with said head offset from the vertical plane through the axis of the wrist pin bosses toward the slotted side of the piston, the connection between said skirt and ring flange being substantially uniform in thickness on the opposite side of the piston.

2. A piston composed of a light metal alloy and including a head having a depending ring flange and a skirt, diametrically opposed wrist pin bosses in the skirt, the upper edge of said skirt being continuously integral with the lower edge of the ring flange on one side of a vertical plane through the axis of the wrist pin bosses and being partially separated therefrom on the opposite side of such plane by a substantially horizontal slot, and reenforcing bridge work comprising a pair of upwardly extending ribs integral with the wrist pin bosses and the ring flange and integrally joined by a rib projecting from the under side of the piston head, all of said re-enforcing bridge work being offset from the vertical plane through the axis of the wrist pin bosses toward the slotted side of the piston.

3. A piston composed of a light metal alloy and including a head having a depending ring

flange, a substantially cylindrical skirt carrying axially aligned wrist pin bosses, said skirt on one side of the vertical plane through the axis of the wrist pin bosses being partially separated 5 from said ring flange by a substantially horizontal slot and having a substantially vertical slot intersecting said horizontal slot and terminating above the lower end of the skirt, the upper edge of said skirt being continuously integral with 10 said ring flange on the other side of such plane through a connection of substantially uniform thickness, and reenforcing ribs integral with said wrist pin bosses and said head offset from the vertical plane through the axis of the wrist pin 15 bosses toward the slotted side of the piston.

4. A piston composed of a light metal alloy and including a head having a depending ring flange, a substantially cylindrical skirt carrying axially aligned wrist pin bosses, said skirt on one 20 side of the vertical plane through the axis of the wrist pin bosses being partially separated from said ring flange by a substantially horizontal slot and having a substantially vertical slot intersecting said horizontal slot and terminating 25 above the lower end of the skirt, the upper edge of said skirt being continuously integral with said ring flange on the other side of such plane, and reenforcing bridge work comprising a pair of upwardly extending ribs integral with the wrist pin 30 bosses and the ring flange and integrally joined by a rib projecting from the under side of the piston head, all of said re-enforcing bridge work being offset from the vertical plane through the axis of the wrist pin bosses toward the slotted 35 side of the piston.

5. An internal combustion engine piston composed of a light metal alloy consisting of a head having a depending ring flange and a substantially cylindrical skirt carrying axially aligned 40 wrist pin bosses, the upper edge of said skirt being partially integral with the lower edge of said ring flange and being partially spaced therefrom, with a greater extent of the integral connection between the skirt and the ring flange on one 45 side of the piston with respect to the vertical plane through the axis of the wrist pin bosses than on the other side of the piston, and vertical reenforcing ribs integral with said wrist pin bosses and with the ring flange and head, all of said ribs 50 being offset toward said last mentioned side of the piston.

6. A piston for internal combustion engines composed of a light metal alloy and including a head having a depending ring flange and a 55 skirt having opposed thrust faces and carrying axially aligned wrist pin bosses, the upper edge of said skirt being partially integral with the lower edge of said ring flange, one of the thrust faces of said skirt being slotted, and substantially vertical reenforcing ribs integral with said wrist pin bosses and with said ring flange and said head, all of said ribs being offset toward the slotted thrust face of said skirt from the vertical 60 plane through the axis of said wrist pin bosses.

65 7. A one-piece aluminum alloy piston for an internal combustion engine comprising a head having a substantially cylindrical depending ring flange, a skirt having wrist pin bosses formed therein and having its upper edge continuously integral with said ring flange on one side of a vertical plane through the wrist pin axis, and partially separated from said ring flange by a horizontal slot on the other side of such plane, where-

by a smaller cross-sectional area of metal for transmitting loads between the head and wrist pin bosses exists on the slotted side of said piston than on the opposite side, and re-enforcing ribs integral with said wrist pin bosses, said ring 5 flange, and said head offset from the vertical plane through the wrist pin axis toward the slotted side of the piston to substantially equalize the cross-sectional area of the metal connecting the head and skirt on the opposite sides of such 10 vertical plane.

8. In internal combustion engine piston composed of a light metal alloy consisting of a head having a depending ring flange and a substantially cylindrical skirt carrying axially aligned wrist 15 pin bosses, the upper edge of said skirt being partially integral with the lower edge of said ring flange and being partially separated therefrom, with a greater extent and cross-sectional area of the integral connection between the skirt and the 20 ring flange on one side of the piston with respect to the vertical plane through the axis of the wrist pin bosses than on the other side of the piston, and vertical re-enforcing ribs integral with said wrist pin bosses and with the ring flange and head 25 offset toward said last mentioned side of the piston and having a cross-sectional area sufficient to uniformly distribute the loads between the head and the wrist pin bosses to said two sides of the 30 piston.

9. A one-piece light metal alloy piston for an internal combustion engine comprising a head having a substantially cylindrical depending ring flange, a skirt having wrist pin bosses formed therein and having its upper edge continuously integral with said ring flange on one side of a vertical plane through the wrist pin axis, and partially separated from said ring flange by a horizontal slot on the other side of such plane, whereby a smaller cross-sectional area of metal for 40 transmitting loads between the head and wrist pin bosses exists on the slotted side of said piston than on the opposite side, and re-enforcing ribbing integral with said wrist pin bosses, said ring flange and said head, the center of mass of all of 45 said ribbing as a unit being offset from the vertical plane through the wrist pin axis toward the slotted side of the piston, said ribbing comprising a substantially straight rib integral with and projecting from the underside of said piston head 50 offset from said vertical plane through the wrist pin axis toward the slotted side of the piston, and downwardly extending ribs integral with said ring flange and with the ends of said first mentioned rib. 55

10. A piston composed of a light metal alloy and including a head having a depending ring flange and a skirt, diametrically opposed wrist pin bosses in the skirt, the upper edge of said skirt being continuously integral with the lower edge of the ring 60 flange on one side of a vertical plane through the axis of the wrist pin bosses and being partially separated therefrom on the opposite side of such plane by a substantially horizontal slot, and re-enforcing bridge work comprising a pair of vertically extending ribs connected to the wrist pin bosses and integral with the ring flange and integrally joined by a rib projecting from the underside of the piston head, all of said reenforcing bridge work being offset from the vertical plane 65 through the axis of the wrist pin bosses toward the slotted side of the piston. 70
